(57) **CLAIM**

The ornamental design for a weed puller, as shown and described.

DESCRIPTION

FIG. 1 is an upper right front isometric view of the weed puller.

FIG. 2 is a front view of the weed puller.

FIG. 3 is a rear view of the weed puller.

FIG. 4 is a left side view of the weed puller.

FIG. 5 is a right side view of the weed puller; and,

FIG. 6 is an enlarged bottom view of the weed puller.

The broken lines in the drawings illustrate portions of the weed puller and form no part of the claimed design.

1 Claim, 6 Drawing Sheets
